UNITED STATES PATENT OFFICE.

SIDNEY F. HUDSON, OF WENATCHEE, WASHINGTON.

HAY-DIVIDER AND TRACK-CLEARER.

SPECIFICATION forming part of Letters Patent No. 783,957, dated February 28, 1905.

Application filed September 15, 1904. Serial No. 224,566.

To all whom it may concern:

Be it known that I, SIDNEY F. HUDSON, a citizen of the United States, residing at Wenatchee, in the county of Chelan and State of Washington, have invented certain new and useful Improvements in Hay-Dividers and Track-Clearers; and I do hereby declare the following to be a full, clear, and exact description of the invention, such as will enable others skilled in the art to which it appertains to make and use the same.

This invention relates to improvements in hay-dividers and track-cleaners.

The object of the invention is to improve the construction of rods or bars which are adapted to be positioned upon the outer end of a sickle-bar for providing means for dividing mown grass from that uncut and also for cleaning the track by removing the cut from the standing grass.

Another object of the invention is the provision of means upon the shoe of a sickle-bar for separating and turning the standing and also the cut grass when a mower is in operation.

A still further object of the invention is the improvement of the construction of a simple, durable, and inexpensive dividing and cleaning rod employed in the construction of a dividing and cleaning device, which is to be removably connected to a sickle-bar of a mowing-machine.

With these and other objects in view the invention consists in certain novel constructions, combinations, and arrangements of parts, as will be hereinafter fully described, illustrated in the accompanying drawings, and more particularly pointed out in the claims hereto appended.

In the drawings, Figure 1 is a view in side elevation of a device constructed in accordance with the present invention. Fig. 2 is a top plan view of the device depicted in Fig. 1, showing a fragmentary view of a sickle-bar. Fig. 3 is an elevated front view of a device constructed in accordance with the present invention, showing the peculiar construction of the dividing and cleaning rods or bars. Fig. 4 is a sectional view of the shoe, taken on line *a a*, Fig. 1.

Referring to the drawings by reference-num-

mers, 1 designates a sickle-bar, upon the outer end of which is secured a shoe 2. Shoe 2 is provided with integral dividing and track-cleaning rod retaining means.

The integral dividing and track-cleaning rod retaining means comprises in its construction an upper integral curved flange portion 3, which is adapted to engage a portion of the dividing and track-cleaning rod 4. An integral flange or angular extension 5 is formed upon the shoe 2 contiguous to the integral portion 3.

The extension 5 projects at 6 beyond the upper rear portion of the shoe 2 and is curved upwardly at 7. The rod 4 is positioned between the two integral extensions 3 and 5 and is positively secured in such position by means of rivets 8 or the like.

A bifurcated or pronged plate 9 is secured to shoe 2, said plate 9 being provided with a dividing or drag board 10. A dividing and track-cleaning rod 4^a is removably positioned in an apertured portion 11 of dividing-board 10. For the purpose of positively securing the rod 4^a in a comparatively rigid assembled position with board 10 a nut 12 is removably mounted upon the end of rod 4^a between the pronged portion of plate 9.

The salient features of this invention reside in the peculiar construction of the dividing and track-cleaning rods 4 and 4^a, said rods being duplicates in construction; but they vary in size, owing to the positioning of the same upon the shoe 2 and board 10, as heretofore specified. The positioning of rod or member 4^a upon the dividing or drag board 10 in the manner shown and described obviates the necessity of having the same of the same length as rod or member 4, as said rod 4 is positioned nearly above rod 4^a and extends to the rear of the same. Each of the rods extends rearwardly, and beginning at 13 it extends radically upwardly and outwardly, projecting farthest at 14. Thence the rod curves inwardly until it reaches its highest portion and thence inward and downward, as at 15, in approximately a semicircle, terminating in an upward-turned, tipped, or end portion 16, which is curved inward and is formed on a level with the base of the shoe 2.

From the foregoing it will be obvious that I have constructed rods which extend backward, outward, and upward to a distance about the height of the ordinary standing grass or hay, 5 and from this point they turn inward and downward in a circular form until they reach a point level with the base of a shoe or rest on the ground. The extreme end of the rod is gently curved upwardly and inwardly. The 10 fastening means for each of the rods 4 and 4^a is different, as hereinbefore specified; but the construction of the rods or members is similar, although the length thereof varies.

When a mower is in operation, the sickle-bar of which being provided with a shoe having rods constructed in accordance with this invention secured thereto, the standing grass is by the outward extension of the two rods, one above the other, pressed outward from the 15 machine and cut grass. Some of the cut grass invariably falls over against and upon the top of the upper rod and the shorter grass upon the lower rod; but by reason of the descending bend of the rod the grass tends to slide 20 off backward, and if any accumulation occurs the rear end of the rods, with their curved tips, will slide along the ground and quickly ride upon the lower end of the accumulated grass and by their weight pull off the accumulated mass. The weight of the mass, if increasing, will soon bear down sufficiently to cause the lower tip of the rod to drag off the 25 mass. The lower tip, with its inward curve on both of the rods, gives the cut grass a rolling inward motion, which clears or removes 30 it away from the standing grass.

Owing to the peculiar construction of the rods 4 and 4^a, they completely divide the cut and standing grass and turn the cut grass inward, leaving a clear path for the next swath. 40 At the same time said rods will always clear themselves automatically.

From the foregoing description it will be obvious to one versed in the art to which this 45 invention relates that certain alterations, modifications, and changes may be made, and I therefore reserve the right to make such alterations, modifications, and changes as shall fairly fall within the spirit and scope of the 50 present invention.

Having thus fully described my invention, what I claim as new, and desire to secure by Letters Patent, is—

1. In a device of the character described, the 55 combination, of a shoe provided with a plurality of flanges, one of said flanges projecting rearwardly, a rod positioned between said flanges, said rod comprising a single piece of material bent outwardly, upwardly, and downwardly and provided with an inwardly-extending upturned end, a dividing-board secured to said shoe, and a curved rod carried by said dividing-board.

2. In a device of the character described, the combination with a shoe, of a dividing-board 60 having an aperture extending therethrough secured to said shoe, a rod removably positioned within the apertured portion of said board, comprising a single piece of material extending rearwardly, outwardly, and upwardly, and 70 curved downwardly and inwardly terminating in a bent end, and a rod secured to said shoe above said rod carried by the dividing-board.

3. In a device of the character described, the combination with a shoe, of rods of different 75 lengths extending rearwardly from said shoe, each rod comprising a piece of material bent outwardly, upwardly, and downwardly, the downwardly-extending portion of said rod being bent inwardly and terminating in an upward-turned end.

4. In a device of the character described, the combination with a shoe, of a plurality of rods extending rearwardly therefrom, said rods of different lengths, and of similar construction, 85 each rod having its free end positioned in the same horizontal plane.

5. The combination with a support, of a rod of the character described, secured to said support, said rod comprising a piece of material 90 bent outwardly, upwardly, and downwardly, the downwardly-extending portion of said rod projecting below the horizontal plane in which the forward end of the rod is secured, said downwardly-extending portion being bent inwardly and terminating in an upward-turned end. 95

6. In a device of the character described, the combination with a shoe, of rods of different lengths and of similar construction extending 100 from said shoe, the free ends of said rods extending below the horizontal plane of the secured ends thereof.

7. In a device of the character described, the combination, of a shoe provided with parallel 105 flanges, a rod secured between said flanges, a dividing-board secured to said shoe, a rod carried by said board, said rods of similar construction and having their free ends curved downwardly and terminating below the plane 110 in which the opposite ends of the rods are secured.

8. In a device of the character described, the combination with a shoe, of a rod secured to said shoe, said rod provided with a portion 115 curved downward and terminating in an upward-turned end, said end being formed below the front secured end of the rod, and auxiliary dividing and turning means assembled with said rod. 120

In testimony whereof I hereunto affix my signature in presence of two witnesses.

SIDNEY F. HUDSON.
